UNITED STATES PATENT OFFICE

106,195

DESIGN FOR A REFRIGERATOR CABINET

Jeremiah Griffith, New York, N. Y.

Application July 29, 1937, Serial No. 70,721

Term of patent 7 years

To all whom it may concern:

Be it known that I, Jeremiah Griffith, a citizen of the United States, residing at 67 East 128th Street, in the city, county, and State of New York, have invented a new, original, and ornamental Design for Refrigerator Cabinets, of which the following is a specification, reference being had to the accompanying drawing, forming part thereof.

The figure is a front perspective view of the refrigerator cabinet, showing my new design, the rear of the cabinet being identical in appearance with the front.

I claim:

The ornamental design for a refrigerator cabinet, substantially as shown and described.

JEREMIAH GRIFFITH.
